SCOURING MEANS

Alfred M. Goodloe, Roanoke, Va., assignor to
 Metal Textile Corporation, West Orange, N. J.,
 a corporation of Delaware

Application February 10, 1938, Serial No. 189,742

2 Claims. (Cl. 15—209)

This invention relates, generally, to an implement or tool for scraping or abrading surfaces and to clean the same; and the invention has reference, more particularly, to a novel device which is especially adapted for use in removing rust or like products of corrosion, incrustations of dirt, or deposits of other undesired substances from surfaces to which they adhere.

This invention has for an object to provide a novel implement or tool which may be easily grasped and manipulated for rubbing over a surface to be cleaned, and which is provided with a novel working face of abrasive metallic mesh, together with means for both supporting and backing said mesh for functional operation, as well as for detachably mounting said mesh in connection with the handle portion of the tool, subject to removal and replacement when, by wear, the serviceable life of said mesh is at an end. Other objects of this invention, not at this time more particularly enumerated, will be understood from the following detailed description of the same.

An illustrative embodiment of this invention is shown in the accompanying drawing, in which:

Fig. 1 is a side view of the novel abrading tool or scraper according to this invention; Fig. 2 is a top or plan view of the same; Fig. 3 is a longitudinal section therethrough, taken on line 3—3 in Fig. 2; Fig. 4 is a transverse section therethrough, taken on line 4—4 in Fig. 2; and Fig. 5 is a fragmentary face view of a preferred form of metallic mesh for use as the operative facing of the tool or implement.

Similar characters of reference are employed in the above described views, to indicate corresponding parts.

Referring to said drawing, the reference character 10 indicates the backing member. This backing member is preferably made of a relatively soft and more or less springy material. I have found that balsa wood is very well adapted to serve as said backing member, for the reason that the same is of relatively soft character, and on this account will permit the metallic mesh material, hereinafter described, to sufficiently embed itself or be gripped by the comparatively soft body thereof as to hold the mesh fabric against undue creeping or relative movement when backed thereby and rubbed over the surface under treatment. Engaged with said backing member 10, so as to be anchored thereto in upstanding projection from the inner side or face thereof, are one or more externally screw-threaded studs 11. Preferably these studs are

provided with heads 12 disposed in countersunk sockets 13 formed in the outer side or face of said backing member, so as to be disposed within the plane of said side or face. The studs per se extend from said heads 12 through the material of said backing member 10, so that the free end-5 portions thereof project from the inner side or face of the latter as stated. The studs are retained in such affixed relation to the backing member 10 by nuts 14 which are turned home 10 against said inner side or face of the backing member.

Said backing member 10 may be made of any desired peripheral shape and of suitable thickness, but preferably the outer peripheral margins 15 of the outer side or face thereof are rounded as indicated at 15. Formed along the marginal portions of the inner side or face of said backing member 10, is a peripheral raised boss 16, preferably of a substantial width.

The reference character 17 indicates the handle block element of the tool or implement, the same corresponding substantially in peripheral shape and size of the peripheral shape and size of the backing member 10. This handle block is preferably made of a relatively hard and tough material as compared with the softer material of the backing member. I have found that a comparatively hard wood is satisfactory for the purposes, but it will be understood that other materials, such as molded plastics or even metal, can be used therefor if desired. Integrally formed in connection with said handle block, to project downwardly from and contiguous to the peripheral margins thereof, is a gripper bead or flange 18, to the face plane of which the plane of the bottom or inner face of handle block is inwardly offset to thereby provide a receiving space 19 for the marginal portions of the metallic mesh material hereinafter described, when the latter is operatively assembled with the backing member in connection with said handle block. Said handle block is provided with perpendicular through openings 20 corresponding to the positions of the studs 11 of said backing member, so that the latter may extend upwardly through said handle block. Said openings 20, at their upper ends, terminate in diametrically enlarged recesses 21 which are countersunk below the plane of the upper or outer side or face of said handle block. The upper free ends of said studs 11 project into said recesses 21 when said backing member and handle block are assembled together, and detachable wing-nuts 22 are applied to said stud ends 55

for separably retaining said backing member and handle block in such assembled relation.

The working face of the tool or implement is formed by a metallic mesh fabric 23, one or more layers of which are superposed across the outer face of said backing member 10, with their marginal portions 24 turned upwardly around the curved periphery 15 of the latter, and then inwardly across the marginal boss 16 which borders the upper or inner face of said backing member. To so apply said metallic mesh fabric 23 to the backing member 10, the handle block 17 is first released and removed, so that the fabric can be related to the backing member in the manner above stated, after which the handle block is re-engaged over the studs 11, and the wing-nuts 22 are applied and screwed home upon the latter. In this manner, the handle block is forced down toward the backing member, thereby causing the 20 gripper bead or flange 18 thereof to tightly clamp the inturned marginal portions 24 of the fabric 23 between the same and the face of said boss 16; the receiving space 19 inwardly of the gripper bead or flange 18 and the boss 16, which is provided intermediate the handle block and backing member, provides a chamber in which the inwardly protruding margins of the fabric 23 now lodge.

In order to prevent exercise of breaking or splitting strains or stresses upon the relatively soft backing member, stop bosses 25 are formed at the under or inner side of said handle-block concentric to the studs 11. These stop bosses, by engagement with the nuts 14 limit any excess movement of the handle block and backing member one toward the other beyond that required to assure firm gripping of the marginal portions 24 of the fabric 23 by and between the gripper bead or flange 18 and the boss 16.

Owing to the relatively soft character of the backing member material, when the fabric 23 is stretched across the operative face thereof and secured, and when thereafter the fabric thus backed is rubbed back and forth over a surface desired to be abraded or scraped, the upward pressure on the fabric causes the same to press against the relatively yieldable backing member material so as to dig into the same to a limited but sufficient extent to hold the same against creeping, and consequently against pulling or stretching strains which might otherwise tend to disrupt the fabric or otherwise too soon diminish its useful life and functional efficiency.

The metallic mesh fabric may be of various types, and fabricated from any suitable selected metallic strand material. Specifically, however, the most desirable form of mesh fabric is one that is knitted from metallic wire of any desired cross sectional shape. Preferably a metallic wire of flat or ribbon-like form when knitted to provide interlinked loops (see Fig. 5) provides the most efficient form of mesh fabric for abrad-

ing and scraping function, since the twists and bends of the loops formed from such flat or ribbon-like wire produce, throughout the area of the fabric, a multiplicity of comparatively sharp chisel-like projections extending in various angular directions, so that not only is a strong and efficient scraping effect attained in use, but such scraping effect is produced no matter what direction of movement may be imparted to the tool or implement when rubbed upon and over a surface under treatment.

It is desirable to provide the longitudinal sides of the handle block 17 with longitudinally extending and indenting finger grip channels 26 of rounded or concave cross-sectional shape, thereby facilitating the grasping of the tool or implement by the user, and assuring tight hold thereupon when manipulating the same.

From the above it will be apparent that this invention provides a very simple and yet efficient abrading or scraping tool for use in cleaning surfaces to which it is operatively applied. The separable arrangement of the handle block, backing member and metallic mesh fabric permits easy and quick removal of the fabric when worn so that new pieces of fabric may be replaced and the useful life of the tool or implement renewed as often as required.

I am aware that various changes could be made in the above described construction and many apparently widely different embodiments of this invention could be made without departing from the scope thereof as claimed. It is therefore intended that all matter contained in the foregoing description or shown in the accompanying drawing shall be interpreted as illustrative and not in a limiting sense.

I claim:

1. An implement for the purposes set forth, comprising a substantially rigid flat faced backing member, a handle block separably superposed on said backing member, a facing of metallic mesh fabric engaged over said backing member with its marginal portions inturned over and around the peripheral portions of said backing member, said handle block having raised gripping portions on its under side to cooperate with said backing member in gripping said marginal portions of said fabric to hold the same operatively assembled in facing relation to the latter, and means detachably securing said handle block and backing member in operative assembled relation to each other and to said fabric, said backing member consisting in material of comparatively soft character relative to said metallic mesh fabric facing to induce frictional resistance to creeping of the latter thereon.

2. An implement as defined in claim 1, wherein in said backing member is made of balsa wood and said facing comprises a metallic fabric knitted from flat ribbon-shaped wire.

ALFRED M. GOODLOE.
